UNITED STATES PATENT OFFICE.

DAVID M. GRAHAM, OF JUANITA, NORTH DAKOTA, ASSIGNOR OF ONE-HALF TO ANGUS FERGUSON AND ANDREW H. WENTLAND, OF BORDULAC, NORTH DAKOTA.

FEEDER FOR THRASHING MACHINES AND THE LIKE.

Application filed May 5, 1916, Serial No. 95,694. Renewed December 15, 1923.

To all whom it may concern:

Be it known that I, DAVID M. GRAHAM, a citizen of the United States, residing at Juanita, in the county of Foster and State 5 of North Dakota, have invented certain new and useful Improvements in Feeders for Thrashing Machines and the like, of which the following is a specification, reference being had therein to the accompanying 10 drawing.

This invention relates to an improved mechanism for separating grain from the straws initially carrying the grain. Among the objects aimed at, in devising the mechanism herein presented, are the delivering to the thrashing cylinder of the mingled mass of grain and straw more uniformly and evenly than has been possible with mechanisms heretofore used; the economizing of power, and applying it with steadiness; the preliminary preparation of the straws for such constant and uniform feed, whether they are initially in bound bundles with the straws more or less approximately 20 parallel, or whether in masses through which the straws are miscellaneous distributed and intertwined.

The matters of detail incident to the mechanism which is herein presented for 30 illustration, whether details in mechanical construction, or in relationship of parts, and the various movements or operations of the parts, will be fully understood from the illustrations and the description given below.

In the drawings:

Figure 1 is a side elevation of a thresher and separator, together with the rear part of the straw-cutting and feeding mechanism.

Figure 2 is a side elevation of the front part of the straw-cutting and feeding mechanism and of the engine; the two figures, 1 and 2 together, constituting a side elevation of the entire apparatus.

Figure 3 is a side elevation of the engine and the front part of the straw cutter and feeder taken from the side opposite to that shown in Figure 2.

Figure 4 is a side elevation of the rear part of the cutter and feeder and of the thresher and separator taken from the side opposite to that shown in Figure 1; these

figures, 3 and 4 together, constituting a complete side elevation of the entire apparatus.

Figure 5 is a top plan view of the engine and the front part of the straw cutter and feeder.

Figure 6 is a top plan view of the rear 60 part of the cutter and feeder and showing also part of the thresher and separator; these figures, 5 and 6 taken together, showing a complete top plan of the straw cutter and feeder, of parts of the engine and of the 65 thresher.

Figure 7 is a longitudinal vertical section of the parts shown in Figure 6.

Figure 8 is a front end view of the straw-cutting and feeding apparatus.

Figure 9 is a view, partly in elevation and partly in section, of a part of the engine and of the devices for connecting it to the cutter and feeder.

Figure 10 is a view, partly in elevation 75 and partly in section, of one of the straw cutters.

Figure 11 is an edge view of a cutter.

Figure 12 shows a modified form of cutter.

Figure 13 is an edge view of the cutter in Fig. 12.

Figure 14 shows a modified construction of the cutting apparatus.

Figures 15 and 16 show details.

I will specify, somewhat in detail, the mechanical parts which are comprised in the apparatus shown, in order to convey a full understanding of one form of mechanism embodying my improvements.

In the drawings there are shown three main elements in the apparatus, the intermediate element, indicated by A, being the mechanism to which the straw and grain are initially delivered, herein also referred to as the stack holder and wherein they are preliminarily treated before being passed to the thresher and separator, indicated conventionally by B. C similarly indicates an engine or tractor.

Referring to those parts comprised in the element A of the apparatus where the straw is preliminarily received and treated; there is a bottom frame comprising the sills 1 with a suitable number of cross girts. The forward end of this frame is supported directly

on the steering truck wheels 1^a of the thresher and separator. The rear end is supported upon the steering truck wheels 1^b.

5 Herein the words "front" or "forward" will have reference to the direction toward the delivery end of the thresher; and the words "rear" or "rearward" will have reference to the direction toward the front end 10 of the engine in the illustrated arrangement of said parts. The side of the apparatus shown in Figures 1 and 2 will be referred to as the "left hand" side; that shown in Figures 3 and 4 will be referred to as the 15 "right hand" side.

From the bottom frame, comprising the sills and cross girts referred to, there are at the front end of the element A uprights or post structures, each having the part 2, 20 rigidly secured to the bottom frame, and a forward part or extension 2^a arranged to provide openings at 2^b. These are connected at the tops by an upper cross girt 3.

At the rear end of the bottom frame are 25 shorter uprights or posts 2^c, one at the right and one at the left. Each upright 2 is connected to a post 2^c by a longitudinal bar or elevated sill 5. The two rear posts 2^c, 2^c are connected by cross bars 7^b and 69^b.

30 Of course, it will be understood that, as concerns the framework just referred to, it can be modified or can have more or fewer sill and girt parts as required.

The frame parts specified support at the 35 right side the longitudinally extended wall slats 7. The bottom of the chamber or space within the framework consists of an endless apron, to be described.

On the left hand side there is a passage- 40 way or opening from the exterior into this space or chamber. Through this passage-way the grain straw is introduced in large masses such as entire stacks or sub-stacks. The mechanism shown is adapted to have 45 stacks introduced which are eight to ten feet long, from five to seven feet high, and from five to six feet width.

The stacks are preliminarily placed upon a supporting and delivering mechanism or 50 stack guide having bars 8 hinged to the frame, preferably by means of arms 8^a, which extend a short distance outward from the frame. These bars 8 carry an anti-friction floor, shown as composed of a 55 series of rollers 9; and the bars are firmly braced together by one or more cross girts, as at 9^a. The arms 8^a support part of the roller floor section. Between the roller 60 openings or gaps are left in the flooring to permit the escape of stones or foreign objects which may adhere to the bottom part of the straw mass.

The straw mass is advanced into the space in the framework by ropes 10^a and a drag 65 bar 10^b. The latter has fingers or prongs 11

which are thrust at an inclination downward and inward from the rear side of the mass, in order to seat firmly in position the drag bar 10^b, and also insure that the mass, as an entirety, shall be advanced. 14 is a 70 handle secured to the drag bar 10^b whereby an operative can manipulate it and thrust the prongs into the straw at the proper points. When the ropes 10^a and drag bar 10^b are not in operation, they are supported 75 on hooks or brackets 10^c.

The ropes 10^a are connected to the ends, respectively, of the drag bar 10^b and extend to winding drums 10^a on a horizontal longitudinal shaft 10 mounted in the framework 80 along the left hand side and near the top. The power devices for operating the shaft will be described below, it being here noticed that, as the drums are rotated, the cables or ropes and the drag bar draw the mass, as 85 an entirety, over the platform 9 and finally position it upon the endless apron at the bottom of the chamber within the frame.

The bottom apron is composed of slats 90 furnishing a floor 9^a, the slats being secured together either by links or belts and mounted on rollers or sprocket wheels at 9^b. The belts or chains on the upper leg of the conveyer rest upon anti-friction rollers 9^c, while the lower leg of the conveyer rests upon 95 guides or supports 9^d. The upper leg of this carrier apron moves forward. The stack or mass of grain is carried by it toward the straw-cutting mechanism. This comprises 100 an endless carrier in the form of an apron of full width or of several parallel belts or chains 25. These are mounted on drums, rollers or sprockets 24, one at the upper end, and the other at the lower end of the system, the upper being carried by 105 shaft 24^a and the lower one by shaft 24^b mounted in the uprights 2, 2^a. The endless elements are provided at intervals with knives 26 alternating with short teeth 27. The rear leg of the cutter apron or belts 110 moves downward toward the carrier 9^a. The details of these devices will be referred to more fully below.

The grain that is cut and forced through 115 the throatway between the lower drum and the end of the carrier 9^a is received in a chamber or space D. Some of the straws are cut into short lengths; others remain whole, while others are more or less doubled or bent. Three currents of air are forced backward through the chamber D by the fan system 54 (Figs. 7 and 16). The currents are produced by three fans 58, 58^a and 58^b. 58 is the center fan transversely of the machine, and is supported on the shaft 58^c. 120 The fans 58^a, 58^b are at the sides of the machine and have ducts 59 for conveying the air forced by them into the chamber D. The fan 58 has an opening at 56 for the entrance of air and an opening at 57 through 125 130

which the air escapes directly rearward. 55 indicates the casing for these fans. The straw and grain are forced outward from the chamber D through the throat 62^a. Below the chamber is the floor at 65, in which there is formed at 67 a pocket or depression for catching heavy articles foreign to the straw and grain which may accidentally find access to the machine. The straw and grain then are propelled up the wind trunk 29 to the hood 30, whence it drops to the thrashing cylinder 33.

The air delivered from the fans 58, 58^a is supplemented by powerful currents from the fan 64 on the shaft 50 mounted in the casing 60. The fan casing has a downwardly extending lip or flange 61 which guides the air which is forced through the opening 62 into the throat at the bottom 20 of the trunk 29. This casing also has a lip or flange 63^a, adjacent to the opening 63, through which the air is drawn into the fan.

The legs of the apron 25 are thrown out 25 of parallelism and held suitably under tension by means of guide plates 25^a, which are preferably bowed in such way as to take up slack which overcomes the tendency of the cutters of the teeth to commence to turn 30 at the pulleys or rollers with too great suddenness. The shaft 24^a of the upper drum is provided with a balance or fly wheel 22. The cutters 26 are secured to bars 131, which are fastened to the apron or belts 25. 35 Each cutter is formed with a plate 118 and a sharp edge 118^a. (Figs. 10 and 11). It is seated in a groove or rebate 117^a in the bar 131. A bolt 120 passes through it, the bolt having its head 122 seated in a countersink in the back of the bar and being fastened in place by the nut 121.

In the throatway at the front end of the bottom carrier 9^e there is a concave-like device comprising a series of fingers or blades 26^b and a base 26^a which carries them. The fingers 26^b are spaced and situated in such way that the fingers 26 and the teeth 27 on the cutter and breaker can pass between them. And the parts 26^b come so close to 50 the circles of rotation of the drums or wheels 24 that the throatway is properly reduced.

The trunk or duct 29 is connected to the hood 30 the latter fitting over the hopper or feedway 32 immediately above the thrashing cylinder 33, the latter carried by shaft 34. The trunk or upper part 29 of the trunk and the hood 30 are hinged or movably connected to the lower part 66. 55 This upper part and the hood can be drawn forward into the position shown in dotted lines in Figure 7 and can be there fastened by the stay rod 31 having at its rear end a hook that engages with an eye 4 or the cross bar 3.

Power is transmitted to the operative parts of the mechanism from the engine 80, having the traction wheels 1^e and the front steering wheels 1^d, as follows:

118^a indicates the crank shaft for the engine. It is provided with a tight band wheel 117 and a loose wheel 119. 116 is the main belt which, when on the tight wheel 117, transmits power to the pulleys 28^a on the cylinder shaft 34. This shaft 75 has its outer end supported in a brace or bracket bar 38 secured to the side of the thresher. 28 is a belt fitted to a pulley 28^b on the cylinder shaft, this belt also engaging with a pulley 22^a on the upper shaft 80 24^a above specified. The shaft 24^b at the lower end of the cutter system has an outer pulley 51 which is connected by a belt 52 with a pulley 53 on the shaft of the fan, 58, 58^a. It has a pulley 48 which is connected by a belt 49 to the pulley 50^a on the shaft 50 of the large fan. Shaft 24^b has also a third pulley 47 which, by belt 46, is connected to a pulley 45 on the shaft 44^a. 44 is a bevel wheel on this shaft meshing with a bevel wheel 43 on shaft 43^a. 42 is a belt pulley on the latter shaft and is connected by belt 41 to a pulley 40 on the rope winding shaft 10. Cylinder shaft 34 has a pulley 34^a which is connected by a belt 21 to a pulley 20 on the shaft 19. This shaft also carries a gear 19^a meshing with a worm 17^a on an inclined shaft 16. The latter carries a second worm 17 which engages with the worm gear 18 on the shaft of the roller or sprocket wheels at 9^b. 18^a is a cover or guard plate over the gearing at 18. The upper shaft 24^a of the straw cutter and breaker is vertically adjustable, there being 85 adjusting devices at 23 for fixing the position of the bearing. 90

At 15 there is a clutch or disengaging device provided with a lever 15^a for disengaging the shaft 16 from the gear 18.

Suitable belt tighteners are applied 110 where required. 35 (Figure 4) is a tightener wheel for the belt 28, carried by the arm 36 pivoted to the link 37 which, in turn, is secured by a pivot 39 to the brace bar 38.

The belt 41 which drives the rope winding shaft has a tightener pulley 68 mounted on the end of a lever 69 pivoted at 69^a in cross bar 69^b and provided with a guiding and bracing bar 76. The upper end of the lever is connected by a lever 70 to a crank arm 71, which extends upward from the squared part 72 of the shaft 13^a. 12 is a crank arm connected to the shaft 13^a and having a hand rope 13 by which an operative can cause the lever 69 to press the roller 68 against the belt 41 and thus apply power to, and cause the rotation of, the rope winding shaft 10. When he relieves the crank arm 12 of draft, the lever 69 is thrown to an inactive position by the spring 74 fas- 120 125 130

tened to the bracket 75 and the holder 73 on the lever.

The main drive belt 116 is held in position by means of guides of a suitable number. Two of these are shown on the right side of the feeder structure, one at the forward end and one near the rear. Each comprises a vertical bar 114 and top and bottom bars 114^a, together with long vertical rollers 115. These belt guides are supported on stub posts 6 secured to the exterior of the right hand side of the feeder frame.

The engine is peculiarly related to the feeder and thresher. It is provided with a belt supporting system such that the belt can be thrown out of action at any time without dropping it to the ground in the usual manner. It passes through a guide, which is carried by the plate 81 on the right side of the engine, this guide having a supporting base 112 extending laterally outward, upon which is supported a sliding device having the uprights 109 and a bottom slide bar 109^a with a brace 113. Two vertical rollers for guiding a belt are held in this sliding frame. When it is desired to stop the feeder and thresher, the belt holder and guide are pushed outward to cause the belt 116 to engage with the loose idler 119 on the engine shaft. When the feeder and thresher are to be again started, the guide 109, 110, is again drawn inward and the belt restored to the tight pulley 117. The guide is moved laterally by a lever 106 pivoted to a support 105 on the engine and is held in place by guide 107. The lever is connected to the belt guide by an arm 108 projecting inward from the latter.

It is further necessary to have the engine related to the feeder and thresher differently when the apparatus is being transported from place to place, in comparison with the way in which it is related when they are all standing bodily stationary and the engine is used as a motor. When the several elements are to stand bodily stationary, and power is to be transmitted from the engine, I make provision for first shortening the distance between the engine and the thresher to permit the putting of the belt in place, and then for increasing this distance in order to tighten the belt.

The coupler bar of the engine is indicated by 84, which is pivoted at 84^a. 83 is a bar adapted to assist in coupling the engine and also to adjustably space and brace it. This bar 83 is, at its rear end, provided with a plate or flange 90, which is pivotally connected at 90^a to the rear truck of the feeder. The draft is distributed from this truck to one or more points along the bottom frame of the feeder by a hound bar 78, which extends preferably to a point near the rear end of the feeder and is secured to a cross

bar 77. At the rear end the bar 83 has an extension 86 provided with a slot 87 through which passes the main draw bolt 84^a.

When traveling from place to place the bars 83 and 84 are connected by a coupling pin 102 adapted to pass vertically through an aperture 102^a in bar 84 and through an aperture at 88 in bar 83. This coupling pin 102 is supported in a bracket 101. When the machines are standing in operation, the pin 102 is drawn out from the bars 83 and 84 and the latter are slidably connected and are held in proper relation to each other by guide loops 103, 104. The engine is spaced and held against approaching the feeder by a dog 91 engaging with teeth 89 in the upper part of the bar 83. After the belt is in place on the wheels the engine can be advanced a short distance relatively to the bar 83, and the dog 91, traveling along the ratchet teeth 89, prevents any retraction. The operator manipulates these parts readily by a lever 96 pivoted to bracket bar 96^a secured to the side plate 82 of the engine. The lever is firmly held in position by a brace guide 99 and is connected through a link 95 and a crank arm 94^c, to the crank arm 94 on a rock shaft 98 mounted in bearings 98^b on the engine platform 98^c, which arm, in turn, is pivotally connected to an arm 92 on the dog 91. The crank arm 94 is also connected by a chain or cable section 102^b to the upper end of the pin 102. The crank arm 94 has a pin 94^a passing through a slot 93^a in the link 93. The connection between the arm 94 and the link 93, on the one hand, and between the arm and the coupling pin 102, on the other hand, are such that the first part of the movement of the lever 94 insures that the pin shall be in its uppermost position. When the dog 91 is to be held out of action, the lever 96 is thrown rearward far enough to have its detent 97^a engage with one of the rear notches 98^a in the segment 97.

In Figs. 12 and 13 there is shown a modified form of cutter and attachment. 123 is the cutter plate. It is secured by a socketed or grooved plate 125 to a cross bar 124, the latter having a groove 125^a on its outer face in which the plate 125 is fitted. 126 are stud bolts extending back from the cutter plate through the bar 124. The bar is countersunk or socketed on its inner face, as at 127, the sockets receiving the projecting bolts 126 and the nuts which fasten them in place. The cutter 123, proper, is riveted in place between the flanges of the plate 125, as shown at 128.

The manner of using the apparatus above described will be readily understood. Heretofore, when wheat, or the like, has been cut with long straws, the virtual practice 120

has been to form tightly bound bundles immediately after the cutting. These are stacked until ready for thrashing. When grain has been thus bundled for the thrashing machine, it has been supplied to the cylinder either by hand-feeding or automatic band cutters and feeders. The former involves the taking of the bundles by an operative at points near the inlet to the cylinder, cutting the bundles and spreading the straws by hand with an effort to have them fed heads first and in parallelism to the planes of rotation of the cylinder. Of late years many mechanisms have been devised for receiving the bundles at points more remote from the cylinder and taking them by carriers or conveyors toward it, there being devices for cutting the bands and spreading the loosened straws in a manner more or less similar to that followed in the hand operation.

But there is now demand for the stacking of wheat, and the like, without binding the straws into bundles and arranging shocks of the latter preliminary to the time of thrashing. And in some sections of the territory the practice is being adopted of arranging the wheat straw in masses which are large relatively to the ordinary bundles and relatively to the ordinary shocks of eight to twelve of such bundles, though small when compared with the large stacks that are sometimes formed; these masses having the straws more or less indiscriminately commingled therethrough. The stacks referred to, and formed in this newly entering practice, are from eight to ten feet long, from five to six feet wide, and from five to eight feet high. These are arranged somewhat closely together in series or in clusters for convenience of access at the time of thrashing.

The present apparatus is designed not only for taking wheat which has been bundled and preparing it for introduction to the thrashing cylinder, but also for taking these stack masses in dimensions approximating those recited.

Instead of passing streams of bundles, the bands of which are successively cut and whose straws are then spread out in thin strata during their passage to the cylinder, a materially different initial step is here taken. The bundles are placed in the feeder A, one on top of the other, to a depth of six feet, or thereabouts, the forward end of the receiving chamber being kept filled, while those at the rear end of the stack are being moved toward the cutting and breaking devices.

In case the grain has been stacked without bundling, that is, in masses formed of miscellaneous arranged relatively loose straws, they are successively brought by suitable devices to the feeder. For treat-

ing the grain having its straws in either of the conditions specified, the apparatus is first brought to an advantageous position. The engine is so guided as to bring the thresher to a point where it will be correctly placed, and the feeder to such position that the grain can be readily delivered to it. Then the engine is disconnected as a tractor; to do which the pin 102 is drawn out from the bars 83, 84. 70 And the main drive belt 116 is, by the lever 106 and the adjustable belt guide, moved over from the idle wheel 119 to the tight wheel 117. If the belt is not sufficiently tight, the operator, by suitable gearing on the engine, causes it to independently advance a short distance, having thrown the lever 96 so as to permit the dog 91 to ride on and over the ratchet teeth 89. When the belt is sufficiently tight, the advance of the 75 engine is stopped and the dog 91 will prevent its retraction relatively to the feeder and thresher.

The three main elements of the apparatus being now in proper relative position, the 80 procedure is as follows:

Assume that a stack of substantially the dimensions recited has been placed on the intake floor 9, 9^a. The operator grasps the draw bar 10^b or its handle 14 and pulls it 85 over the top of the stack (the rope pulleys at this time being free) and places it at the proper horizontal line across the outer vertical face of the stack, and at the same time throws the prongs 11 into the mass in a 90 downwardly inclined direction so as to apply the draft properly throughout the bottom part thereof. Then, by the pulling device 13, he forces the tightener pulley 68 against the belt 41, whereupon the winding 95 shaft is caused to rotate and wind up the cables 10^d, this resulting in dragging the mass of straws into the feeder A. The carrier 9^e immediately causes it to move toward the cutting apparatus. The cutters 110 26 move rapidly, and, as they descend, engage with such straws as come to them and lie transversely to their paths. The impulse given to the straws and pieces takes them toward the concave. The fingers 26^b act to 115 retard the transversely arranged straws long enough to insure their being cut or disengaged from the mass. Each series of cutters is followed by the blunt tearing or breaking fingers 27, which act to rapidly 120 drag downward and forward the straws or pieces with which they engage. The purpose is to separate each straw or piece as far as possible from the mass and deliver it in this separated relationship to the chamber D. Here the straws or pieces are impinged on by the three currents of air which are directed backward from the fans 58, 58^a. The straws, straw pieces and loose grain are forced by the air jets along the 125 130

6
floor 65 and through the throatway at 62^a, where the powerful and voluminous currents of air from the fan 64 continue their propulsion through the trunk 29 and the hood and to the cylinder.

5 Should relatively small stones, or small pieces of material foreign to the grain, be initially introduced with the straws, their specific gravity is availed of for separating them; for, as they pass along the bottom 65 of the chamber D, they settle in the pocket at 67 and are prevented from passing to the cylinder, from which pocket they can be readily separated.

10 15 As is well known, much loss is caused and frequently great danger to operatives results from the passage of foreign articles to a thrashing cylinder, these being tools, pieces of metal, large stones, or the like, which are enclosed in, and concealed by, the straws that reach the cylinder.

20 25 In case such an article be initially introduced in the present mechanism, it may cause limited damage to the cutting apparatus. But there is practically no danger to those around the machine, and the devices for propelling the material toward the cylinder will insure their separation before it is reached.

30 35 40 45 50 Another serious difficulty in operating ordinary thrashing and separating mechanism is due to the fact that it has been impossible to insure a uniform and even feed continuously for any material length of time. The cutting of the bundles, either by hand or by automatic devices, has resulted in unevenness in the feed, this being so serious at frequent intervals that the rapidly rotating cylinder is slowed down below the proper working speed. An appreciable time is necessary to bring it back to speed again. And as the thrashing cylinder is an excellent source of power for other parts that must be timed with the cylinder, it is generally connected to the various devices which cut the bands and feed the straws; and in the ordinary mechanism, as a consequence of this, the entire apparatus is subject to fluctuations in speeds; and the inertia of the various moving parts has to be overcome at short intervals, both in respect to speeding up and slowing down.

55 In my apparatus the pneumatic feed of the straw and grain to the cylinder overcomes these difficulties, and I deliver practically uniformly a stream of predetermined quantity, per unit of time, as long as the machine is in operation.

60 I do not desire to cut all of the straws into short length. The cutters can, to advantage, be placed so that either those along each bar, or those in the entire series, will travel in transverse planes from two to three inches apart. And this insures that a large percentage of the straws will be cut. The

results in this respect can be varied as desired by employing proper cutter bars suitable for the occasion.

Those straws, however, which approach the cutting and breaking device, longitudinally, or approximately so, will pass through without being broken up or cut.

70 75 The advantage resulting from having a percentage of the long straws pass through is that, after the material has passed the thrashing cylinder and reaches the separating tables, or the like, the mass, considered as an entirety, delivered thereto will have the shorter straws and grain berries commingled with the longer ones and it will be 80 open and porous so that it is subjected to the vibrations of the separating devices, the berries being completely shaken out and separated therefrom.

85 These will comprise, of course, concave straw-shaking devices, winnower, straw-stacking mechanism, etc., of any suitable make. The builder of the machine will employ such devices for transmitting power and for giving the proper speeds to the different operative parts that he sees fit.

90 95 The stacks (indicated by dotted lines at E) are brought in succession, and one after the other is placed in the manner described in the chamber of the feeder. The feed to the cutters and thresher is continuous, as the chamber in the feeder is two or three feet longer than the stack, so that a succeeding mass can be introduced before the preceding one has all been delivered to the cutter and straw breaker.

100 105 110 After the thrashing operation as any one locality has been completed, it is not necessary, with this apparatus, to remove the main drive belt or any of the others. The guides for the belt which have been described are permanently in position and are so disposed as to hold the belt properly, even when the apparatus is being transported. There are two of the guides on the side of the feeder so that when the three elements (engine, feeder and thresher) are on the road and are out of line, the belt will not be displaced, the guide on the engine holding it properly in relation to the pulley 119, and the guides on the feeder holding it properly in relation to the feeder and thresher.

115 120 125 It will be understood that the apparatus is especially adapted for operating on grain, which has been cut so that the straws are of considerable length, and the stacks of which have stood in the field for a period of curing so that they have settled and become compacted and are relatively solid. For the rapid and economical handling of such stacks and the thrashing of the grain straws thereof it is of great advantage to move the stacks bodily and successively into said stack holder, where the grain is re- 130

5 moved or in a manner stripped continuously and evenly from a face of the compacted stack, and converted into a rapidly and continuously moving relatively thin sheet of grain, which is suitably delivered to the thrashing machinery. The stack thus operated upon may be described as of solid cubical form (though usually elongated) and it retains such form during its thrashing, excepting for the continuous and even removal of the grain straws from one of its faces, as above described.

10 What I claim is:

15 1. The combination of an engine, thrashing machinery, a stack holder having walls and having an opening in a vertical wall of the same adapted to have an entire stack of grain, in the form in which such grain is stacked in the field after cutting, inserted therein through said opening by sliding on its bottom, and means for removing grain from said stack when in the stack holder and feeding the same to said thrashing machinery.

20 25 2. The combination of an engine, thrashing machinery, a stack holder having walls and having an opening in a vertical wall of the same adapted to have an entire stack of grain in the form in which such grain is stacked in the field after cutting, inserted therein through said opening, without lifting the same off its bottom, and means for removing grain from said stack when in the stack holder and feeding the same to said thrashing machinery.

30 35 3. The combination of an engine, thrashing machinery, a stack holder having walls and having an opening in a vertical wall of the same adapted to have an entire stack of grain in the form in which said grain is stacked in the field after cutting, inserted therein through said opening, means for supporting the stack while resting on its bottom as it is inserted in the stack holder, and means for removing grain from said stack when in the stack holder and feeding the same to said thrashing machinery.

10. The combination of an engine, thrashing machinery, a stack holder having walls and having a stack-receiving opening in one of its upright walls adapted to have a formed stack of grain, as it is made in the field after cutting, inserted therein through said opening, means for removing grain from said stack when in the stack holder and feeding the same to said thrashing machinery, and means for advancing the stack as a formed entirety against said removing and feeding means. 65
11. The combination of an engine, thrashing machinery, a stack holder having walls and having a stack-receiving opening in one of its upright walls, adapted to have a formed stack of grain, as it is made in the field after cutting, inserted therein through said opening, a stack guide leading to said opening, means for advancing a stack along said guide, means for removing grain from said stack when in the stack holder and feeding the same to said thrashing machinery, and means for advancing the stack as a formed entirety against said removing and feeding means. 75
12. The combination of an engine, thrashing machinery, a stack holder having walls and having a stack-receiving opening in one of its upright walls, adapted to have a formed stack of grain, as it is made in the field after cutting, inserted therein through said opening, a stack guide leading to said opening, a winding draft means actuated by the thrashing engine for advancing a stack along said guide, means for removing grain from said stack when in the stack holder and feeding the same to said thrashing machinery, and means for advancing the stack as a formed entirety against said removing and feeding means. 80
13. The combination of an engine, thrashing machinery, a stack holder having a stack-receiving opening in one of its upright walls adapted to have a formed stack of grain, as it is made in the field after cutting, inserted therein through said opening, means for removing grain from along a face of said stack when in the stack holder and feeding the same to said thrashing machinery, and means for advancing the face of the stack as a formed entirety against said removing and feeding means. 85
14. The combination of an engine, thrashing machinery, a stack holder having walls and having a stack-receiving opening in one of its upright walls adapted to have a formed stack of grain, as it is made in the field after cutting, inserted therein through said opening, an endless belt having means for removing grain from along a face of said stack when in the stack holder and feeding the same to said thrashing machinery, and means for advancing the stack as a formed entirety against said removing and feeding means. 90
15. The combination of an engine, thrashing machinery, a stack holder adapted to have an entire stack of grain in the form in which such grain is stacked in the field after cutting, inserted therein, means for removing grain from said stack when in the stack holder, and pneumatic means for feeding the same to said thrashing machinery. 95
16. The combination of thrashing machinery, a stack holder having a lateral stack-receiving opening and a grain delivery opening, a stack-advancing conveyer at the bottom of the stack holder, an endless grain carrier operating along a face of the stack and towards said grain delivery opening for separating and removing the grain from the stack for delivery through said opening to the thrashing machinery, means for advancing a stack of grain laterally through said stack-receiving opening and into the stack holder and on to the advancing conveyer, and means for advancing the stack bodily towards said endless carrier. 100
17. The combination of thrashing machinery, a stack holder having a lateral stack-receiving opening near the ground, an inclined stack guide leading to said opening, draft means for drawing a stack of grain on said guide through said opening and into said stack holder, means for removing the grain from said stack and feeding it to the said thrashing machinery, an engine, and means for connecting the thrashing machinery and stack holder and engine in spaced relation. 105
18. The combination of thrashing machinery, a stack holder adapted to hold a stack of grain of substantially solid cubical form, means acting parallel with and along a face of said stack for removing grain therefrom and propelling it in a continuous thin sheet, means for feeding said sheet of grain to said thrashing machinery, and means for propelling said stack to the said grain-removing means. 110
19. The combination of an engine, thrashing machinery, a stack holder having means for propelling a stack of grain endwise therein, a driving belt from the engine to the thrashing cylinder shaft, an endless belt having means operating along a face of the stack for removing grain therefrom, means for driving said endless belt rapidly from the thrashing cylinder shaft, means for feeding the removed grain to the thrashing cylinder, and means for driving the said stack-propelling means slowly from the thrashing cylinder shaft. 115
20. The combination of thrashing machinery, a stack holder having stack enclosing walls formed with a lateral opening for the entrance of a stack of grain and adapted 120

- to have an entire formed stack of grain inserted therein, a movable bottom for the stack holder, a stack guide leading to the top of said movable bottom, a substantially vertical and downwardly acting endless belt having means for removing grain along a face of the stack and forming with said bottom a throat for the exit of the grain so removed, means for delivering such grain to the thrashing machinery, and means for moving said bottom towards said belt. 5
21. The combination of thrashing machinery, a stack holder, an endless belt having means operating along a face of the stack for removing grain therefrom, means for feeding the removed grain to said thrashing machinery, and a support for the operating part of said belt acting to hold it in proper relation to said face of the stack. 15
22. The combination of thrashing machinery, a stack holder adapted to have an entire formed stack of grain inserted therein, a movable bottom for the stack holder, a substantially vertical and downwardly acting endless belt having means for removing grain along a face of the stack and forming with said bottom a throat for the exit of the grain so removed, a grain passage leading from said throat and having a pocket for heavy foreign substances, means for delivering grain from said passage to the thrashing machinery, and means for moving said bottom towards said belt. 25
23. The combination of thrashing machinery, a stack holder adapted to have an entire formed stack of grain inserted therein, a movable bottom for the stack holder, a substantially vertical and downwardly acting endless belt having means for removing grain along a face of the stack and forming with said bottom a throat for the exit of the grain so removed, pneumatic means for delivering such grain to the thrashing machinery, and means for moving said bottom towards said belt. 30
24. The combination of thrashing machinery, a stack holder adapted to have an entire formed stack of grain inserted therein, a movable bottom for the stack holder, a substantially vertical and downwardly acting endless belt having means for removing grain along a face of the stack and forming with said bottom a throat for the exit of the grain so removed, means for delivering such grain to the thrashing machinery comprising air forcing devices and air ducts delivering into the sides of the grain passage near said throat, and means for moving said bottom towards said belt. 35
25. The combination of thrashing machinery, a stack holder adapted to have an entire formed stack of grain inserted therein, a movable bottom for the stack holder, a substantially vertical and downwardly acting endless belt having means for removing grain along a face of the stack and forming with said bottom a throat for the exit of the grain so removed, a grain passage beyond said throat, a fan delivering air into said passage, a duct leading from said passage to the thrashing machinery, a fan delivering air into said duct in the direction of the movement of the grain, and means for moving said bottom towards said belt. 40
26. The combination of thrashing machinery having a closed hood over the grain entrance thereto, a stack holder having an opening for the insertion of a formed stack of grain and a grain delivery opening, means for removing and freeing grain from the inserted stack to said delivery opening, and pneumatic means for feeding the same to said closed hood. 45
27. The combination of an engine, thrashing machinery, an intermediate stack holder, means for feeding the grain of a stack to said thrashing machinery, a driving belt from said engine to the thrashing machinery, devices for actuating said feeding means, and means for shifting said engine belt. 50
28. The combination of an engine, thrashing machinery, an intermediate stack holder, means for holding said elements in spaced relation, and a driving belt from said engine to the thrashing machinery, the spacing means having extensible parts provided with a ratchet connection. 55
29. In a stack holder adapted to be used with thrashing machinery and an engine, the straw removing belt adapted to act along a face of the stack, upwardly curved straw breakers removably attached to said belt, and straw removing means arranged on said belt between said straw breakers. 60
30. In a stack holder adapted to be used with thrashing machinery and an engine, and having means for feeding loosened grain straws to such thrashing machinery, and having an open side, the combination of a winding drum mounted on said stack holder, opposite to said open side, ropes attached to said drum, a stack engaging device attached to said ropes and having prongs to enter within the outer side of the stack, and means for actuating said winding drum from the thrashing engine. 65
31. In a thresher feeding mechanism the combination with the thrashing devices, means to elevate straw to said devices from a relatively low horizontal plane near the ground surface, a holder for a relatively large loose straw stack, means for withdrawing a stream of straw from the said stack while the stack as an entirety is in the holder, the holder having a side wall and a rear end wall which are fixed while in operation and the opposite side wall being open for the admission of a straw stack while moving into the holder along a horizontal axis. 70

zontal plane below the tops of the said walls, the latter extending from the horizontal plane aforesaid to a horizontal plane near the top of the stack.

5 32. In a thresher feeding mechanism the combination with the thrashing devices, means to elevate straw to said devices from a relatively low horizontal plane near the ground surface, a holder for a relatively 10 large loose straw stack, means for withdrawing a stream of straw from the said stack while the stack as an entirety is in the holder, the holder having upright stack-confining walls which are fixed while the machine is in operation and one of which is open for the admission of a straw stack while moving into the holder on a horizontal plane below the tops of the said walls, the latter extending from the horizontal plane aforesaid to 15 a horizontal elevated plane.

20 33. In a thresher feeding mechanism the combination with the thrashing devices,

means to elevate straw to said devices from a relatively low horizontal plane near the ground surface, a holder for a relatively 25 large loose straw stack, means for withdrawing a stream of straw from the said stack while the stack as an entirety is in the holder, the holder having upright stack-confining walls which are fixed while the machine is in operation and one of which is open for the admission of a straw stack while moving into the holder on a horizontal plane below the tops of the said walls, the latter extending from the horizontal plane aforesaid to a horizontal plane to which the straw is elevated.

In testimony whereof, I affix my signature, in presence of two witnesses.

DAVID M. GRAHAM.
